Eric Winston, Melrose Park, and Edward M. Frank,
Churchville, Pa., assignors to Jerrold Electronics
Corporation, Philadelphia, Pa., a corporation of
Delaware

Filed Oct. 18, 1968, Ser. No. 14,061

Term of patent 14 years

Int. Cl. D14—03

U.S. Cl. D26—5

FIG. 1

FIG. 2

FIG. 3

FIG. 4

FIG. 1 is a top view of the housing;
FIG. 2 is a front view of the housing of FIG. 1;
FIG. 3 is a bottom view of the housing of FIG. 1;
FIG. 4 is an end view of the housing of FIG. 1.
The housing is basically rectangular, having cable
receptacles at each end, and a clamp upon the top for
suspending the housing from a messenger cable. Fittings
to which distribution cables are attached extend from
a protrusion on the bottom, and angle downwardly there-
from toward each end of the housing.

We claim:

The design for a signal distribution housing for CATV,
as shown and described.
